Des. 206,006

Patented Oct. 18, 1966

206,006

CIRCUIT BREAKER

William W. Camp, Lawrence Township, Mercer County, and Charles Mune, Trenton, N.J., assignors to Heine-mann Electric Company, Trenton, N.J., a corporation of New Jersey

Filed Mar. 29, 1965, Ser. No. 84,484

Term of patent 14 years

(Cl. D26—13)

FIG. 1 is a front perspective view of a circuit breaker showing our new design;

FIG. 2 is a side elevational view thereof;

FIG. 3 is a top plan view thereof;
thereof;

FIG. 4 is a front elevational view thereof;

FIG. 5 is an enlarged front elevational view of a portion of the circuit breaker, the actuating lever being omitted for convenience of illustration;

FIG. 6 is a partial, bottom plan view thereof, but viewed from the bottom of FIG. 5;

FIG. 7 is a cross-sectional view thereof taken on line 7—7 of FIG. 5; and

FIG. 8 is a cross-sectional view thereof taken on line 8—8 of FIG. 5.

The essential features of our design are shown in full lines in the drawings.

We claim:

The ornamental design for a circuit breaker, as shown and described.
